UNITED STATES PATENT OFFICE.

LENA B. PALMER, OF GLENDALE, CALIFORNIA.

WOOLEN UNDERGARMENT.

1,176,977.

Specification of Letters Patent. Patented Mar. 28, 1916

Application filed July 19, 1915. Serial No. 40,714.

To all whom it may concern:

Be it known that I, LENA B. PALMER, a citizen of the United States, residing at Glendale, in the county of Los Angeles and State of California, have invented a new and useful Woolen Undergarment, of which the following is a specification.

In washing woolen undergarments soap cannot be directly applied to the garments without causing them to become dense, hard and unpleasant to the skin due to shrinkage. The object of this invention is to provide a woolen undergarment with gussets or insets of easily washable and non-shrinking material at the points most apt to become soiled. The principal points of this character are the arm pits and the crotch. The gussets or insets are preferably made of cotton, which will withstand vigorous rubbing and to which soap may be directly applied without causing undue shrinkage, but they may be made of any other suitable material having the said properties.

In the accompanying drawing the single figure shows one style of union suit having insets at the crotch and arm pits according to the present invention.

Undergarments differ widely in style and shape and in each case the gussets should be made of proper size and shape to accomplish the desired purpose. An approximately diamond shape is usually suitable for the gussets under the arms and each should be made large enough to prevent the surrounding wool from becoming stained in use and from coming in contact with the soap in washing. The inset *d* employed in the crotch is preferably of the shape shown in the figure in the style of garment illustrated. In garments which are split all the way down the front and which have flaps at the seat, the flaps should be made of the washable material in addition to the surrounding portion shown in the drawing.

The inset material should be of substantially the same weight as the woolen portion of the garment and may either be woven into

the garment or secured therein in some such manner as the arms are commonly attached to the trunk. The diamond shaped inset under the arm may either be in two pieces as shown at *a* and *b* at the left of the figure, in which case the member *a* forms a part of the sleeve and the member *b* forms a part of the trunk, or the inset may be made of a single piece of material *c* as shown at the right of the figure.

In this specification I have described the preferred embodiment of my invention, but it is to be understood that I contemplate other arrangements. Furthermore, many changes or modifications of the invention illustrated will readily occur to those skilled in the art and therefore I do not desire to be limited to the exact arrangement shown and described but aim to cover all such changes and modifications as come within the spirit and scope of the appended claims.

What I claim as new and desire to secure by Letters Patent of the United States, is:

1. A woolen garment having insets of cotton in the arm pits and in the crotch, whereby the parts of the garment most apt to be soiled may be effectively cleansed.

2. A woolen garment having gussets in the arm pits, said gussets forming parts of the garment and being made of cotton or the like which may be more easily and effectively cleansed than wool, substantially as shown and described.

3. A woolen undergarment having insets of cotton in the arm pits, said insets being diamond shaped and woven integrally with the garment, forming parts of the garment. substantially as shown and described.

4. In a woolen undergarment, arm pits formed of cotton gussets, said gussets being integral with and forming parts of the garment.

5. An undergarment, said undergarment being composed of wool except diamond shaped parts in the armpits and crotch, said parts being composed of cotton.

LENA B. PALMER.
